TARGET THROWING DEVICE

Francis G. du Pont, Utica, N. Y., assignor to
Remington Arms Company, Inc., Bridgeport,
Conn., a corporation of Delaware

Application November 20, 1945, Serial No. 629,813

8 Claims. (Cl. 124—8)

1 The present invention relates, in general, to target throwing devices, and, in particular, to improvements in traps such as used in trap and skeet shooting.

In using target throwing traps and especially the trap shown and described in the copending application of Rutherford et al., Serial No. 519,722, filed January 26, 1944; now Patent No. 2,432,446, issued December 9, 1947; the throwing arm is secured to a carrier head and is held in cocked position by engagement of a pawl, pivotally mounted on the carrier head, with a manually actuated or spring loaded trigger. When the throwing arm is in cocked position, the mutually engaging surfaces of the pawl and trigger are under load due to the force of the tensioned main spring acting to swing the throwing arm and carrier head around through the throwing arc. The release of the throwing arm is accomplished by withdrawing the trigger from engagement with the pawl. It has been found that disengagement of the trigger and pawl when under load causes excessive wear on their mutually engaging surfaces which ultimately interferes with the satisfactory operation of the trap.

An object of the invention is the provision of improved means for latching the trap throwing arm. A further object is to provide improved trap latching means which may be quickly and conveniently operated to release the trap and which will withstand long periods of service without exhibiting excessive wear.

These and other objects, features and advantages of the invention will be more particularly described in the following specification, reference being made to the drawing in which:

Fig. 1 is a schematic perspective view of a target throwing trap embodying the improved latching means of this invention.

Fig. 2 is a fragmentary plan view of the trap of Fig. 1 showing the cocking and releasing mechanism for the throwing arm and including the improved latching means of this invention, the carrier head being in its normal position prior to cocking.

Fig. 3 is a fragmentary plan view similar to Fig. 2, but with the carrier head held in cocked position.

Fig. 4 is a fragmentary front elevation of the trap cocking and releasing mechanism in the direction of arrows 4—4 of Fig. 2.

Referring to the drawing, the trap shown in Fig. 1 is described in detail in the above-identified Rutherford et al. application and is illustrative only of a target throwing device to which the improved latching means of this invention is applied.

2 cable. It will be understood that the invention may have other uses and is limited only by the scope of the appended claims.

Briefly, the trap comprises a base 10 having a bracket 11 on which is mounted the trap frame, indicated generally at 12, and which constitutes a flanged beam 13 having a depending web 14 to accommodate fastening means for securing the beam to the bracket 11. The forward end of the beam 13 terminates in a hook-shaped head which comprises vertically spaced substantially parallel upper and lower flanges 15 and 16 respectively, see Fig. 4, connected by a substantially vertical web member. The flanges 15 and 16 are provided with vertically aligned bushed apertures to receive a post 17, the upper end of which projects above the upper flange 15 and constitutes an axis for the carrier head 18, the latter being freely rotatable thereon. The carrier head is connected by means of a link 19 having a bevelled shoulder 19' to the forward end of the main spring 20, the rear end of the latter being suitably secured to the rear end of the beam 13. The bevelled shoulder 19' of the link is adapted to be engaged by a correspondingly bevelled shoulder 22 of the carrier head as the latter approaches the end of the throwing arc to rapidly decelerate the throwing arm. The throwing arm 21 is secured to the top planar surface of the carrier head 18 and is moved into cocked position by means of a ratchet disk 23 and pawl assembly. The ratchet disk 23 is rotatably mounted on the post 17 between the upper and lower flanges 15 and 16 of the frame and is provided on its bottom surface and adjacent its periphery with an integral bifurcated lug 24, see Fig. 4, to which is pivoted the forward end of the cocking bar 25. Suitable ratchet teeth 26 are formed on one edge of the disk 23. At substantially the opposite side of the disk 23 is a depending lug 27 which is formed integrally with or otherwise secured to the underside of the disk.

The carrier head 18 has a substantially vertical radially extending web portion 28 at the outer end of which is a boss 29. A hole extends upwardly in this boss from the underside thereof for receiving a pawl pivot pin 30 which is adapted to pivotally support a pawl on the underside of the boss 29. The pawl is adapted normally to engage a tooth of the ratchet disk 23 so that by pulling rearwardly on the cocking bar 25 of the disk, the carrier head and throwing arm 21 will be rotated clockwise into cocked position in which position the carrier head is temporarily held against the force of the tensioned main spring 20 by a trigger and trigger locking mechanism.

As mentioned above, in the trap of the Rutherford et al. application the carrier is held in cocked position by engagement of a pawl with the trigger which may be operated manually or by means of a spring to release the pawl.

The description thus far has been a general one of a trap of the type shown in Fig. 1. The present invention relates to an improved latching means for holding the carrier head and throwing arm in cocked position. Referring to Fig. 2, the boss 29 of the carrier head 18 is shown provided with a lateral extension 32 having at its outer end an integral depending lug 33 which is a substantially rectangular parallelepiped having a square shoulder 34 at one end and a bevelled shoulder 35 at its opposite end. A recess 36 is provided on the inner face of the lug and constitutes a seat for one end of a pawl spring 37, the opposite end of which is adapted to engage in a recess 38 in the adjacent side of a pivoted pawl 39. The pawl 39 has a tooth 40 depending from its forward end adapted normally to be held in engagement with a tooth 26 of the ratchet disk 23 by the force of the pawl spring 37. The opposite or rear end of the pawl is tapered to form a lever arm 42, the end of which is provided with a V-shaped notch 43 as shown in Fig. 4.

The trigger for latching and releasing the cocked carrier head is shown at 44 and comprises an arm mounted between the upper and lower flanges of the frame by a vertically disposed pivot pin 45 intermediate the ends of the trigger arm. A cylindrical boss 46 is shown on the upper surface of the trigger arm and slightly eccentric to the pivot pin 45. This boss constitutes a hub about which are encircled the coils of a substantially U-shaped trigger spring, indicated generally at 47, and comprising two resilient arms 48 and 49. The arm 48 hereafter termed the forward arm lies in a horizontal plane above the horizontal plane of the ratchet disk 23 (Fig. 4) in line with the apex of the V-shaped notch 43 of the pawl arm 42. The rear arm 49 of the trigger spring encircles a second hub 49' on the trigger and lies in a horizontal plane beneath the ratchet disk 23 and in the path of the depending lug 27.

The rear end portion of the trigger 44 is substantially identical to the corresponding portion of the trigger used in the Rutherford et al. trap and embodies a curved edge 50 arranged to be cooperatively engaged by the correspondingly curved edge 52 of the spur 53 of a pivoted locking lever 54. The latter is biased by a spring 55 normally to pivot counterclockwise and automatically lock the trigger in the manner and for the purpose described below.

The opposite or forward end of the trigger 44 is provided with an integral substantially U-shaped upstanding flange 56 along its outer edge. The rearwardly disposed leg 57 of the flange 56 is provided with an adjustable stop 58. The forwardly disposed leg 59 of the flange constitutes a guard which partially encircles a cylindrical roller 60 supported to rotate freely on a vertical pin 62 secured at the forward end of the trigger.

The operation of the improved latching means is as follows: Assuming the carrier head and ratchet disk are in their normal positions, as shown in Fig. 2, the lug 27 of the disk 23 will be in engagement with the rear arm 49 of the trigger spring and tension the same sufficiently to rotate the trigger 44 clockwise, thus throwing the forward end of the trigger outwardly. In order to cock the throwing arm, the operator pulls the cocking bar 25 rearwardly rotating the ratchet

disk 23 clockwise. Since the tooth 40 of the pawl 39 is normally held in engagement with a tooth 26 of the ratchet disk by the force of the pawl spring 37, the carrier head 18 and throwing arm 21 will be rotated clockwise. Continued rotation of the ratchet disk in this direction will eventually carry the tapered end 42 of the pawl against the forward arm 48 of the trigger spring, the arm 48 engaging in the V-shaped notch 43 of the pawl. The clockwise rotation of the ratchet disk has, of course, carried the lug 27 out of engagement with the rear arm 49 of the trigger spring and consequently the trigger 44 will be biased by the energy of the tensioned fore-arm 48 and pivoted counterclockwise bringing its forward end into juxtaposition with the lug 33 of the carrier.

Further clockwise rotation of the ratchet disk and carrier head is prevented when the square shoulder 34 of the lug 33 engages the adjustable stop 58 of the trigger. In this position of the carrier head, the bevelled shoulder 35 of the lug is in engagement with the roller 60 of the trigger, as shown in Fig. 3. Initially, however, the load, that is to say, the force of the tensioned main spring 20 which has been tensioned by the clockwise rotation of the carrier head, is still carried by the pawl 39. Concurrently, the counterclockwise displacement of the trigger has withdrawn its rear end from in front of the spur 53 of the pivoted trigger lock 54 and the latter, urged by the force of the tension spring 55, pivots counterclockwise and positions the curved edge 52 of the spur in front of the curved edge 50 of the trigger so as to block the clockwise rotation of the latter.

To release the carrier head and throwing arm, the operator moves the cocking bar 25 forwardly so as to return the ratchet disk 23 to its original position. As the ratchet disk begins to rotate counterclockwise, the load formerly carried by the pawl 39 is transferred to the mutually engaging surfaces of the lug 33 and trigger roller 60. During this transfer, the trigger 44 tends to pivot clockwise due to the force component of the load acting parallel to the bevelled surface 35, and may move very slightly in this direction. However, any appreciable displacement of the trigger is prevented by the trigger lock 54 which, as described above, blocks clockwise rotation of the trigger. Since the pawl has been relieved of the load, the force of the tensioned trigger spring arm 48 acting on the reduced end 42 of the pawl pivots the latter clockwise against the relatively light force of the pawl spring 37, thereby disengaging the pawl tooth 40 from a corresponding tooth of the ratchet disk as shown in Fig. 3.

As the ratchet disk approaches its original position, its depending lug 27 first engages the rear arm 49 of the trigger spring 47 so that the latter is energized to rotate the trigger clockwise. Concurrently, a shoulder 63 (Fig. 2) on the bottom of the ratchet disk engages a resiliently mounted post 64 which serves to indicate to the operator that the ratchet disk is approaching trap releasing position, and, thereafter, the depending lug 27 engages the rear end 54 of the trigger lock and positively pivots the lock clockwise so as to unlock the trigger. The latter, urged by the tensioned trigger spring 47 and the force component acting along the bevelled surface 35 of the lug, swings clockwise and releases the carrier and throwing arm. The force of the tensioned main spring 20 then swings the throwing arm and carrier around rapidly counterclockwise through the throwing arc.

As the carrier and throwing arm begin to rotate, the pawl tooth 40 is initially held out of engagement with the teeth 26 of the ratchet by the fore-arm 48 of the trigger spring acting on the rear end of the pawl but as the carrier continues to rotate, this end of the pawl is carried away from the spring arm 48, whereupon the force of the compressed pawl spring 37 rotates the pawl counterclockwise about its pivot 30. However, before the pawl tooth 40 is permitted to engage a tooth 26 of the ratchet, the pawl tooth overtakes a pawl guard, indicated generally at 65, which intervenes between the pawl tooth and the teeth of the ratchet disk thus enabling the pawl to pass freely over the teeth of the ratchet. The pawl guard 65 is described more fully in the above-identified Rutherford et al. application and briefly comprises a thin sheet metal member rotatable about the post 17 and having a reach provided with two upstanding laterally spaced stops 66 and 67 arranged on opposite sides respectively of the web 28 of the carrier head. The outer end of the reach has a guard finger 68 adapted to extend over the teeth 26 of the ratchet disk. The lateral spacing of the stops 66 and 67 is designed to provide an interval of lost motion between the movement of the guard finger 68 and that of the carrier head whenever the latter changes its direction of rotation. Thus, when the carrier head is released, the guard finger 68 is momentarily immobile and hence is overtaken by the pawl which engages and rides up on the guard finger 68 out of possible contact with the teeth of the ratchet disk.

As the carrier head approaches the end of its throwing arc, its bevelled shoulder 22 engages the bevelled shoulder 19' of the main spring link 19 which rapidly decelerates the carrier and throwing arm. The carrier head then reverses its direction of rotation, and the pawl guard finger 68 lags behind the pawl sufficiently to leave the teeth of the ratchet disk uncovered, thus enabling the spring biased pawl to swing into engagement with a tooth of the disk for recocking the throwing arm.

What is claimed is:

1. A device for throwing targets comprising a base; a frame supported on said base; a carrier having a target throwing arm; means for rotatably supporting said carrier on said frame; a main spring connected to said carrier; means for cocking said carrier comprising a rotatable ratchet disk, a member to rotate said disk, and a pawl mounted on said carrier, said pawl being arranged normally to engage said ratchet disk and carry the load effected by tensioning the main spring during the cocking of said carrier; and carrier latching means comprising a trigger mounted on said frame and a resilient element associated with said trigger, said resilient element being arranged to be engaged and actuated by said pawl during the cocking of said carrier to move said trigger into latching engagement with said carrier.

2. A device for throwing targets comprising a base; a frame supported on said base; a carrier having a target throwing arm; means for rotatably supporting said carrier on said frame; a main spring connected to said carrier; means for cocking said carrier comprising a rotatable ratchet disk, a member to rotate said disk, and a pawl mounted on said carrier, said pawl being arranged normally to engage said ratchet disk and carry the load effected by tensioning the main spring during the cocking of said carrier; and carrier latching means comprising a trigger mounted on said

frame and a spring associated with said trigger arranged normally to bias said trigger in inoperative position and to be energized by said pawl during the cocking of said carrier to swing said trigger into latching engagement with said carrier.

3. A device for throwing targets comprising a base; a frame supported on said base; a carrier having a target throwing arm; means for rotatably supporting said carrier on said frame; a main spring connected to said carrier; means for cocking said carrier comprising a rotatable ratchet disk, a member to rotate said disk, and a pawl mounted on said carrier, said pawl being arranged normally to engage said ratchet disk and carry the load effected by tensioning the main spring during the cocking of said carrier; and carrier latching means comprising a trigger mounted on said frame and a spring associated with said trigger, said spring being arranged to be engaged and energized by an element of said ratchet disk when said carrier is in its normal uncocked position to hold said trigger in inoperative position and to be energized by said pawl during the cocking of said carrier to move said trigger into latching engagement with said carrier.

4. A device for throwing targets comprising a base; a frame supported on said base; a carrier having a target throwing arm; means for rotatably supporting said carrier on said frame; a main spring connected to said carrier; means for cocking said carrier comprising a rotatable ratchet disk, a member to rotate said disk, and a pawl mounted on said carrier, said pawl being arranged normally to engage said ratchet disk and carry the load effected by tensioning the main spring during the cocking of said carrier; and carrier latching means comprising a trigger mounted on said frame and a spring associated with said trigger arranged normally to bias said trigger in inoperative position and to be energized by said pawl during the cocking of said carrier initially to swing said trigger into latching engagement with said carrier and thereafter to disengage said pawl from said ratchet disk.

5. A device for throwing targets comprising a base; a frame supported on said base; a carrier having a target throwing arm; means for rotatably supporting said carrier on said frame; a main spring connected to said carrier; means for cocking said carrier comprising a rotatable ratchet disk, a member to rotate said disk, and a pawl mounted on said carrier, said pawl being arranged normally to engage said ratchet disk and carry the load effected by tensioning the main spring during the cocking of said carrier; and carrier latching means comprising a trigger mounted on said frame and a spring associated with said trigger arranged normally to bias said trigger in inoperative position and to be energized by said pawl during the cocking of said carrier initially to swing said trigger into latching engagement with said carrier and thereafter to hold said pawl out of engagement with said ratchet disk during the initial movement of said carrier when released.

6. A device for throwing targets comprising a base; a frame supported on said base; a carrier having a target throwing arm; means for rotatably supporting said carrier on said frame; a main spring connected to said carrier; means for cocking said carrier comprising a rotatable ratchet disk, a member to rotate said disk, and a pawl mounted on said carrier having a lever arm, said pawl being arranged normally to engage said

ratchet disk to carry the load effected by tensioning the main spring during the cocking of said carrier; and means to latch the carrier in cocked position comprising a trigger, a resilient element associated with said trigger and arranged to be energized by the lever arm of said pawl during the cocking of said carrier to swing said trigger into carrier latching position and an element on said carrier constructed and arranged to engage said trigger when said carrier is in cocked position to transfer the load of said tension main spring from said pawl to said trigger.

7. A device for throwing targets comprising a base; a frame supported on said base; a carrier having a throwing arm; means for rotatably supporting said carrier on said frame; a main spring connected to said carrier; means for cocking said carrier comprising a ratchet disk rotatable freely on said carrier supporting means, a pawl mounted on said carrier and arranged normally to engage a tooth of said ratchet disk to couple said disk to said carrier, and a member to rotate said disk thereby to swing said carrier into cocked position and tension said main spring; and means to latch said carrier in cocked position comprising a trigger mounted on said frame and a trigger spring associated with said trigger, said trigger spring comprising a pair of resilient arms, one of said arms being arranged to be engaged by an element of said ratchet disk when said carrier is in its normal uncocked position to hold said trigger in inoperative position, the other arm of said spring being arranged to be engaged by said pawl during the cocking of said carrier to swing said trigger from its inoperative position into latching engagement with said carrier.

8. A device for throwing targets comprising a base; a frame supported on said base; a carrier having a throwing arm; means for rotatably supporting said carrier on said frame; a main spring connected to said carrier; means for cocking said carrier comprising a ratchet disk rotatable freely on said carrier supporting means, a pawl mounted on said carrier and arranged normally to engage a tooth of said ratchet disk to couple said disk to said carrier, and a member to rotate said disk thereby to swing said carrier into cocked position and tension said main spring; and means to latch said carrier in cocked position comprising a trigger mounted on said frame and a trigger spring associated with said trigger, said trigger spring comprising a pair of resilient arms, one of said arms being arranged to be engaged by an element of said ratchet disk when said carrier is in its normal uncocked position to hold said trigger in inoperative position, the other arm of said spring being arranged to be engaged by said pawl during the cocking of said carrier initially to swing said trigger into latching engagement with said carrier and thereafter to disengage said pawl from a tooth of said ratchet disk.
